No. 36,350.

Patented June 2, 1903.

UNITED STATES PATENT OFFICE.

ROBERT STOCK, OF BRIDGEPORT, CONNECTICUT.

DESIGN FOR A TABLE-MAT.

SPECIFICATION forming part of Design No. 36,350, dated June 2, 1903.

Application filed January 17, 1903. Serial No. 139,488. Term of patent 7 years.

To all whom it may concern:

Be it known that I, ROBERT STOCK, a citizen of the United States, residing at Bridgeport, in the county of Fairfield and State of Connecticut, have invented a new, original, and ornamental Design for Table-Mats, reference being had to the accompanying drawing, which is an elevation illustrating my design.

I claim—

The ornamental design for a table-mat, as shown.

In testimony whereof I affix my signature in presence of two witnesses.

ROBERT STOCK.
